RADIO TRANSMITTER ANTENNA REEL.

Elmer C. Moore, Glenview, Ill.

Application May 20, 1938, Serial No. 209,106

3 Claims. (Cl. 242—99)

The present invention relates to a radio transmitter antenna reel designed primarily for use upon aircraft for winding in or letting out the radio antenna, and has for its primary object to provide a reel of this character in which the antenna will be automatically maintained either in a partly or completely wound position on the reel without necessitating any special locking means for securing the reel against movement.

An important object of the present invention is to provide a reel of this character embodying spring means between the reel and hub on which the reel is mounted and providing friction gripping contact therewith to secure the reel in a predetermined position.

Another object is to provide a reel of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part thereof, wherein like numerals refer to like parts throughout, and in which

Figure 1 is a side elevational view.

Figure 2 is a front elevational view of the attaching plate showing the hub secured thereon.

Figure 3 is a rear elevational view of the manipulating handle.

Figure 4 is a vertical transverse sectional view.

Figure 5 is a side elevational view of the spring.

Figure 6 is a fragmentary sectional view showing the anchoring means for one end of the spring, and

Figure 7 is a sectional view taken substantially on a line 7—7 of Figure 4.

Referring now to the drawings in detail, the invention comprises an attaching plate 5 to the front surface of which is secured a hub 6 by screws or the like 7, said hub having a central threaded recess 8 within which the reduced threaded end 9 of a handle attaching pin 10 is threadedly engaged. The handle is indicated at 11 and is provided on its inner surface with a hub portion 12 abutting the hub 6 and through which the pin 10 is freely inserted, the outer end of 50 the handle being provided with a manipulating knob 13.

The hub 6 also includes an annular skirted portion 14 disposed in spaced relation outwardly from the hub portion and upon said skirted portion 55 is positioned a spirally wound spring 15 hav-

ing flat convolutions as more clearly shown in Figure 4 of the drawings, one end of the spring terminating in a laterally off-set eye 16 engaged by a pin 17 recessed in the inner surface of a reel 18 for anchoring said end of the spring to 5 said reel. The opposite end of this spring is formed with a radial extension 19 adapted to be received in a notch or recess 20 formed in the outer surface of the reel 18 adjacent the inner periphery of the reel. In assembling the spring 10 on the hub and the reel on the spring in the position shown in Figure 4, a groove 21 is formed on the inner periphery of the reel to accommodate the extension 19 of the spring.

The inner face of the handle 11 is provided 15 with a lug 22 also adapted to seat in the notch 20, said notch being of sufficient area to permit slight play between the lug 22 and extension 19 during the manipulation of the handle, as will be apparent from an inspection of Figure 7 of 20 the drawings.

The reel 18 is loosely mounted on the spring 15 and the diameter of the spring 15 is slightly less than the diameter of the skirted portion 14 of the hub to cause a normally frictional engagement therebetween. Accordingly, by reason of this frictional engagement, the reel 18 will be held against idle rotation on the hub 6, although free to be rotated to wind or unwind an antenna thereon by reason of the engagement of the lug 30 22 of the handle with the recess or notch 20 of the reel.

Also by reason of the play provided in the notch or recess 20 with the extension 19 of the spring, the manipulation of the handle in one 35 direction will serve to expand the spring 15 to decrease its frictional engagement with the hub 6, thus permitting a free and rapid rotation of the reel.

The spring further is mounted in a manner so 40 that the manipulation of the handle and reel in an opposite direction will cause a release in the tension of the spring through the connection of the eye 16 with the reel, thus reducing frictional engagement between the spring and hub when the 45 reel is manually operated in either direction, but providing for friction gripping engagement between the spring and hub when the reel is idle.

One portion of the reel is provided with a counter-sunk recess 23 to enable the knotted 50 ends of the wire to be soldered to the reel.

It is believed the details of construction and manner of operation of the device will be readily understood from the foregoing without further detailed explanation.

Having thus described the invention what I claim is—

- 5 1. A reel of the class described comprising a stationary hub, a spirally wound spring surrounding said hub, a reel freely mounted on said hub outwardly of the spring, means fixedly connecting one end of the spring to said reel, a radial extension on the other end of the spring, a notch in the reel accommodating said extension, a handle rotatably mounted on the hub and a lug on the handle and inserted in said notch for rotating the reel, said lug also being engageable with the extension to expand the spring upon rotation of the reel in an opposite direction.
- 10 10 2. A reel of the class described comprising a stationary hub, a spirally wound spring surrounding said hub in normal frictional engagement therewith, a reel freely mounted on said hub outwardly of the spring, means fixedly connecting one end of the spring to the reel, the other end of the spring being loose, a handle rotatably carried on the hub and means carried by the handle and having direct operating engagement with the reel for rotating the same in one direction, the loose end of the spring being interposed between the reel and said operating means in its opposite movement to initially release the spring from the hub and to subsequently contact the reel to rotate the reel in 15 said opposite direction.
- 15 20 20 3. A reel of the class described comprising a stationary hub, a spiral spring surrounding said hub in frictional engagement therewith, a reel mounted on the hub outwardly of the spring, means fixedly connecting one end of the spring to the reel, the other end of the spring being loose, a handle rotatably carried on the hub and means carried by the handle and having direct operating engagement with the reel for rotating the same in one direction, the loose end of the spring being interposed between the reel and said operating means in its opposite movement to initially release the spring from the hub and to subsequently contact the reel to rotate the reel in 20 said opposite direction.

ELMER C. MOORE.
